UNITED STATES PATENT OFFICE.

THEODOR GÜNSEL, OF NEW YORK, N. Y.

DESIGN FOR A BANNER-HOLDER.

SPECIFICATION forming part of Design No. 23,258, dated May 8, 1894.

Application filed March 8, 1892. Serial No. 424,227. Term of patent 3½ years.

To all whom it may concern:

Be it known that I, THEODOR GÜNSEL, a citizen of the United States, residing in the city of New York, county of New York, and State of New York, have invented and produced a new and original Design for Banner-Holders, of which the following, in connection with the accompanying drawing, is a full and complete description.

10 The leading feature of my design is a tubular cylindrical block having radial diverging arms projecting from its upper periphery, in an oblique direction.

15 In the accompanying illustration A designates the cylindrical block and the projecting divergent radial arms are designated by the letters B, B.

C designates an opening through the block A, and D, D, designate depressions or holes in the arms B, B. 20

What I claim is—

The design for a banner holder, substantially as shown and described.

In testimony that I claim the foregoing as my invention I have signed my name, in presence of two witnesses, this 7th day of March, 1892. 25

THEODOR GÜNSEL.

Witnesses:

E. F. GENNERT,
WM. F. CULLEN.
